(57) CLAIM

The ornamental design for an applicator, as shown and described.

DESCRIPTION

FIG. 1 is a perspective view of an applicator showing our new design.

FIG. 2 is a front view thereof.

FIG. 3 is a rear view thereof; and,

FIG. 4 is a left side view thereof.

The applicator is axially symmetric such that top and bottom views are the same as the left side view, and the right side view is a mirror image of the left side.

1 Claim, 4 Drawing Sheets

FIG. 1

FIG. 4
